UNITED STATES PATENT OFFICE.

RUDOLF LORENZ, OF ESSEN, GERMANY, ASSIGNOR TO FRIED. KRUPP AKTIENGESELLSCHAFT, OF ESSEN-ON-THE-RUHR, GERMANY.

SURFACE CONDENSER.

Application filed July 17, 1925, Serial No. 44,403, and in Germany August 14, 1924.

This invention relates to surface condensers of the kind in which the condensation takes place in a nest of tubes with which a cooling medium is brought into contact, and it resides essentially in that the spaces between the condenser tubes are filled up by filling bodies with a large surface.

On the drawings is illustrated in

Fig. 1 an embodiment of the subject-matter of the invention in vertical section, in Fig. 2 a section along the line 2-2 of

Fig. 1,

Figs. 3 and 4 show a second embodiment in views similar to Figs. 1 and 2,

15 Figs. 5 and 6 show a third embodiment.

In the embodiment of Figs. 1 and 2 A denotes the condenser casing which has a rectangular cross-section and in the upper part of which are disposed the condenser tubes B. The condenser tubes are arranged in groups and fastened by their ends in the side walls a^1 and a^2 of the condenser casing. The condenser tubes open into chambers C and D which are attached to the side walls a^1 and a^2 of the condenser casing.

The chamber C is connected with the exhaust steam conduit E, while the chamber D receives the water of condensation which flows through a pipe F to a collecting tank (not shown). Arranged above the condenser tubes B and extending in the same direction as the same are pipes G with apertures g^1 through which the cooling water trickles down over the condenser tubes. The cooling water accumulates on the bottom a^3 of the condenser casing A and flows off through a pipe H. The casing wall a^1 has connected to it a pipe J for the admission of cooling air. The cooling air is carried off through a pipe K which is connected to the cover a^4 of the condenser casing A. The spaces between the tubes B are filled up by filling bodies L with a large surface, such as e. g.

40 pipe-pieces or spirally wound strips of sheet metal. The filling bodies L rest on screen-like plates M which are carried by the upper layer of the groups of tubes formed by the condenser tubes B.

45 If the condenser tubes B are arranged sufficiently close to each other, the filling bodies L may be laid directly on the upper layer of the groups of tubes. The condenser tubes B may also be uniformly distributed in the

upper part of the condenser casing A and the filling bodies L arranged so that they fill up all spaces remaining between the tubes.

In view of the foregoing, a detailed description of the general operation of the condenser does not seem necessary.

The area of contact between the cooling water and the cooling air is essentially enlarged by the filling bodies L so that the delivery of heat to the cooling water takes place in a considerably higher degree than in the case the cooling water trickles simply over the condenser tubes. Therefore, the efficiency of the condenser is materially increased by the described arrangement without it being necessary to change the dimensions of the condenser.

70 In the embodiment shown in Figs. 3 and 4 a screen O is arranged immediately above the water distributing pipes N, which has likewise put on it a layer of filling bodies P. By these filling bodies the cooling air is forced to deliver again the water which has been carried along with it from the condenser.

75 In the embodiment of Figs. 5 and 6 a screen R is arranged immediately above the uppermost row of condenser tubes Q, and filling bodies are put thereon up to a level such as to cause the water supply pipes T to be surrounded from all sides by the filling bodies. This arrangement results in a very uniform distribution of the cooling water. At the same time water is prevented thereby from being carried out with the cooling air leaving the condenser.

Claims:

80 1. A surface condenser, comprising a nest of spaced condensing tubes, means for supplying a cooling liquid and bringing it into contact with the tubes, and filling bodies of large surface filling the spaces between said tubes.

85 2. A surface condenser, comprising a plurality of condensing tubes, means for supplying a cooling liquid and bringing it into contact with the tubes, the tubes being arranged in superimposed groups and the spaces between the groups filled up with filling bodies of large surface, and means for conducting a current of air upwardly through said groups of tubes.

90 3. A surface condenser, comprising a plu-

- rality of condensing tubes, sprinkler tubes bringing cooling water into contact with the condensing tubes, the spaces between the condensing tubes and the space above said 5 sprinkler tubes being filled up by filling bodies of large surface, and means for conducting a current of air upwardly between said tubes.
4. A surface condenser, comprising a plu-
10 rality of condensing tubes, sprinkler tubes bringing cooling water into contact with the condensing tubes, the spaces between the condensing tubes and the space surrounding said sprinkler tubes being filled up by filling 15 bodies of large surface, and means for conducting a current of air upwardly between said tubes.

5. A surface condenser, comprising a plu-
rality of condensing tubes arranged in su-
perimposed groups, sprinkler tubes bringing 20 cooling water into contact with the condens-
ing tubes, the spaces between the groups of
condensing tubes and the space surrounding
said sprinkler tubes being filled up by filling
bodies of large surface, and means for con-
ducting a current of air upwardly through
said groups of tubes.

The foregoing specification signed at
Cologne, Germany, this 29th day of June,
1925.

RUDOLF LORENZ.
